[57]**CLAIM**

The ornamental design for a combined cap and razor holder, as shown and described.

DESCRIPTION

FIG. 1 is a front elevational view of a combined cap and razor holder showing my new design;
 FIG. 2 is a top plan view thereof;
 FIG. 3 is a rear elevational view thereof; and,
 FIG. 4 is a side elevational view thereof, the opposite side elevational view being a mirror image thereof.
 The structure shown in broken lines is for illustrative purposes, and forms no part of the claimed design.
